UNITED STATES PATENT OFFICE

165,596

DEEP FAT FRYER

Jack Morgan, Chicago, Ill., assignor to Dormeyer Corporation, Chicago, Ill., a corporation of Illinois

Application March 13, 1951, Serial No. 14,471

Term of patent 14 years

(Cl. D81—10)

To all whom it may concern:

Be it known that I, Jack Morgan, a citizen of the United States, residing in the city of Chicago, county of Cook and State of Illinois, have invented a new, original, and ornamental Design for a Deep Fat Fryer, of which the following is a specification, reference being had to the accompanying drawings, forming a part thereof:

Fig. 1 is a perspective view of a deep fat fryer showing my new design;

Fig. 2 is a side elevational view of one side thereof, the other side being substantially the same;

Fig. 3 is a top plan view thereof with the interior shown as seen through the transparent cover;

Fig. 4 is a front elevational view thereof;

Fig. 5 is a rear elevational view thereof; and

Fig. 6 is a bottom view thereof.

The side not shown is substantially like the side shown in Fig. 2.

This is a continuation-in-part of my application, Serial No. D-11,695, filed August 9, 1950.

I claim:

The ornamental design for a deep fat fryer, as shown and described.

JACK MORGAN.
